UNITED STATES PATENT OFFICE.

UBALDO BERETTA AND BENVENUTO GIANESE, OF GENOA, ITALY.

STEAM-BOILER.

1,084,782.

Specification of Letters Patent.

Patented Jan. 20, 1914.

Application filed March 19, 1912. Serial No. 684,735.

To all whom it may concern:

Be it known that we, UBALDO BERETTA and BENVENUTO GIANESE, both subjects of the King of Italy, residing at Genoa, Italy, have 5 invented certain new and useful Improvements in Steam-Boilers, of which the following is a specification.

Our invention has for its object to provide an apparatus to be used in steam boilers of 10 every type for improving the combustion.

It is well known that part of the volatile material contained in the coal is not consumed but leaves the chimney without contributing in any way to the efficiency of the 15 boiler.

It is the object of the present invention to construct an apparatus permitting the products of combustion to combine with the oxygen of the atmospheric air introduced into 20 the combustion chamber and of increasing in this manner the efficiency of the coal burnt on the grate.

In the accompanying drawing Figure 1 is a longitudinal vertical section through part 25 of a boiler embodying our invention. Fig. 2 is a longitudinal horizontal section thereof, and Fig. 3 is a detail view illustrating the manner of securing the pipes and staffs. Fig. 4 is a section on line 3—3, Fig. 2, and 30 Fig. 5 is a detail top plan view of a staff and plates.

Into the secondary combustion chamber of a boiler as shown in Fig. 1 a plurality of 35 plate elements B composed of refractory material is introduced. These elements become incandescent at about 1400° F. and produce a better chemical affinity between the products of combustion and the oxygen of the atmospheric air. These plate elements are 40 supported by the staffs A composed of refractory material (principally magnesia silicates), of about 3600° F. fire resistance. The staffs A are secured in the pipe T³ and extend through the pipe G⁴ as shown in Fig. 3.

The oxygen of the atmospheric air which 45 enters a chemical combination with the volatile materials of the coal is introduced by means of the pipes T¹ which traverse the combustion chamber and are arranged with 50 in two heating pipes T² of the furnace (see Figs. 1 and 2). The air entering into the pipes T¹ is heated by the influence of the boiler water and while traveling through the pipes T² its temperature is increased, where- 55 after it passes into the secondary combustion

chamber and passes the open holes in the pipes T⁵ and T⁴ opening into pipes T³. A valve V at one end of the pipe T¹ controls the regulation of the air which is supplied. The two pipe pieces T⁴ are secured to the 60 heating pipes by means of a tie-rod L, nut and lock nut C and D. As a supplementary means for more intimately mixing the oxygen of the atmospheric air and the combustion gases a certain quantity of air is also 65 introduced and distributed by means of a flue K.

It is generally known that the gases leaving the furnace at a speed of about 16 to 20 feet per second are rapidly contacting with 70 the tube plate and consequently suffer a considerable loss of temperature of about 930° F. and become well adapted for the production of soot. This is a frequent occurrence especially with the ordinary marine boilers 75 and locomotive boilers.

With the present appliance the gases are obliged to travel a longer distance within the combustion chamber being restrained by said appliance and obliged to pass across it. 80 Thus a supplemental combination of the products of combustion and the oxygen of the atmospheric air is produced in the combustion chamber of a boiler, which combination produces an increase of temperature and 85 a considerable decrease in the smoke developed and consequently an important increase in the efficiency of the boiler.

It is clear that the staff A may be made of any suitable material, shape, and may be 90 differently arranged, and that the elements B may be substituted by elements of any other suitable incandescent material and finally also the pipes T¹, T³, and T⁴ may be arranged in any different suitable way without departing from the scope of the present 95 invention.

We claim:

1. A tubular boiler having a passage for the products of combustion, in combination 100 with upper and lower pipes extending from the tubes of the boiler into said passage and provided with openings discharging air into said passage, a plurality of perforated circular plate elements of refractory material interposed in the path of the products of combustion to retard the passage of the same and spaced from each other, inclined staffs of refractory material mounted on said pipes 105 and extending across the path of the prod- 110

ucts of combustion for supporting said plate elements, substantially as and for the purpose set forth.

2. A tubular boiler having a passage for
5 the products of combustion, in combination
with upper and lower pipes extending from
the tubes of the boiler into said passage and
provided with openings discharging air into
said passage, staffs mounted on said pipes
10 and extending across the path of the prod-
ucts of combustion at an angle to the verti-

cal, and flat perforated plates of a refractory material mounted on said staffs in spaced relation with respect to each other, substantially as described.

15 In testimony whereof we affix our signatures in presence of two witnesses.

UBALDO BERETTA.

BENVENUTO GIANESE.
